UNITED STATES PATENT OFFICE.

SAMUEL C. KEENE, OF BOSTON, MASSACHUSETTS.

SIGN.

949,578.

Specification of Letters Patent. Patented Feb. 15, 1910.

Application filed April 7, 1909. Serial No. 488,429.

To all whom it may concern:

Be it known that I, SAMUEL C. KEENE, of Boston, in the county of Suffolk and State of Massachusetts, have invented a certain 5 new and useful Improvement in Signs; and I do hereby declare the following to be a full, clear, and exact description of the same, reference being had to the accompanying drawings, forming a part of this specification, and to the figures and letters of 10 reference marked thereon.

This invention relates to improvements in signs especially adapted for window advertising and it has for its object to provide 15 a frame in which the letters or other characters may be readily mounted and changed as desired.

To these ends the invention consists in certain novel details of construction and 20 combinations and arrangements of parts all as will be now described and the particular features of novelty pointed out in the appended claims.

In the accompanying drawings wherein is 25 illustrated the preferred embodiment of the invention—Figure 1 is a perspective view of the sign constructed according to the present invention; Fig. 2 is a view looking toward the inside of one of the sides of the 30 frame, a carrier for the letter being shown in section; Fig. 3 is a top view of one of the carriers partly broken away, the side of the frame in section; Fig. 4 is a perspective view of a letter; Fig. 5 is a detail perspective view of one of the letter bars or carriers 35 partly broken away; Fig. 6 is a detail view showing the jointing at the ends of the frame sections.

Similar letters of reference in the several 40 figures indicate the same parts.

Referring to the drawings, the frame is preferably rectangular and consists of the top and bottom sections A—A' and side sections B—B' of any suitable material, but 45 preferably wood. As shown, the side sections B—B' near each end are formed with a shoulder b, which fits upon the ends of the top and bottom sections A—A', the parts being united by means of screws b², as will be 50 readily understood. By such construction the frame may be readily taken apart for storage or transportation, and be set up quickly, requiring no particular skill on the part of the user for this purpose. The 55 frame may be provided with eyes c⁶, by means of which it may be suspended. The

side sections B—B' of the frame are each rabbeted as at b³, and in this rabbeted portion are mounted the supports for the bars or carriers for the letters. As shown, these 60 supports take the form of right angle hooks b⁴, which are arranged in a vertical row and suitably spaced apart, see Fig. 1. The bars or carriers for the letters rest at each end upon these hooks, as shown clearly in the 65 drawings. In the present embodiment these carriers C consist of metal strips bent into substantially U-form, by which construction an unobstructed channel or recess is obtained for the reception of the letters D extending 70 the length of the carrier. By this means a single support suffices for a line of characters.

Ordinarily, the letters would be held firmly within the channel of the strip or 75 bar and be kept in proper position, but to avoid any possibility of the letters slipping or falling over, a spring metal strip c is secured to one wall of the channel extending the entire length thereof and this strip 80 is preferably corrugated, as shown, the letters D being each provided or formed with an extension or neck d, also preferably fluted or corrugated. By such a construction the neck d can be readily inserted 85 within the channel in the carrier, and then by a slight sidewise movement be locked firmly in place, due to the coöperation of the corrugations on the neck d of the letters and in the strip c, as will be readily understood. 90

The distance between the hooks b⁴ is slightly less than the width of the bars or carriers C, so that in order to remove or position the carriers a slight tilting of the 95 bar is necessary. By this arrangement the letters may be removed from the carriers without removing the bars from the frame without danger of the bars being lifted off the hooks.

In order to conceal the hooks b⁴ so that the frame may have a neat appearance, the side sections B—B' of the frame are provided with hinged strips B² which may be closed as shown at the left in Fig. 1, the 105 top and bottom sections of the frame being cut away as at b⁵ to receive the strip B². This hinged strip B² may, if desired, be provided with a series of pins b⁶, so positioned as to extend over the top of the bars or carriers C when the strip is closed, as shown in Fig. 2; thus still further insuring the keep- 110

ing of the bars in place, as will be understood.

By this construction, signs may be readily made up or changed without requiring special skill, and in the case of window advertising little light is obstructed.

While the frame is especially adapted for window advertising, it is also well adapted for interior advertising in general, and may 10 be used for educational purposes.

Having thus described my invention, what I claim as new and desire to secure by Letters Patent of the United States, is—

1. In a device such as described, the combination with a holder, of an integral U-shape metal strip carried by said holder, letters or characters each having a single tab or extension adapted to be inserted and means for locking said characters in the 20 strip at any desired point.

2. In a device such as described, the combination with the frame, of a single, integral carrier for the letters having a channel or recess extending the entire length of 25 the carrier, a spring strip within said channel, and letters or characters formed with extensions adapted to fit in the channel of the carrier and against which the spring strip bears, whereby each letter or charac-

ter will be held in position, substantially as 30 described.

3. In a device such as described, the combination with the frame, of the U-shape metal carrier, the corrugated metal strip within the channel of said bar, and the letters or characters having corrugated extensions adapted to coöperate with the corrugations on the strip, whereby said letters will be locked in position, substantially as 35 described.

4. In a device such as described, the combination with the frame, of the channel bars, hooks arranged in a vertical series on each side of the frame upon which said channel bars rest, letters or characters 40 adapted to be removably mounted in said bars, the distance between the hooks being less than the width of the bars, whereby the letters may be removed from the bars without removing the bars from the frame, 50 substantially as described.

5. A letter or character for use in interchangeable signs formed with a corrugated holding extension.

SAMUEL C. KEENE.
